BY

INVENTOR
John Taylor.

ATTORNEY

UNITED STATES PATENT OFFICE.

JOHN TAYLOR, OF SALT LAKE CITY, UTAH.

COAL-DUST FURNACE.

Application filed May 23, 1921. Serial No. 471,793.

To all whom it may concern:

Be it known that I, JOHN TAYLOR, a citizen of the United States, residing at Salt Lake City, in the county of Salt Lake, in 5 the State of Utah, have invented certain new and useful Improvements in Coal-Dust Furnaces, of which the following is a specification.

This invention relates to coal dust furnaces adapted to burn fine fuel in suspension and it has for its object to provide improved means to bring about an intimate mixture of coal dust with the necessary air to support substantially perfect combustion.

10 Briefly stated my improved furnace comprises a primary combustion chamber and a secondary combustion chamber; fine fuel in suspension in a stream of air entering the primary combustion chamber and being ignited therein and the products of combustion passing from the rear end of this primary combustion chamber into a secondary combustion chamber from which heat is reflected back into the primary combustion 15 chamber for the purpose of raising the temperature of the incoming fuel. The arrangement of the parts is such as to bring about a whirling movement of the fuel and the products of combustion so that an intimate 20 mixing of the fine fuel and air and the previously ignited gases is brought about with a consequent marked increase in efficiency.

Further objects and advantages of the invention will be set forth in the detailed description which follows.

In the accompanying drawings:

Fig. 1 is a front elevation of the furnace of my invention illustrating the door thereof and the controlling latches for the same;

40 Fig. 2 is a transverse vertical sectional view of the furnace upon line 2—2 of Fig. 4;

Fig. 3 is a plan view of the furnace with the cap of the secondary combustion chamber removed;

45 Fig. 4 is a longitudinal vertical section upon line 4—4 of Fig. 2;

Fig. 5 is a transverse vertical sectional view of a modified form of the furnace upon line 5—5 of Fig. 7;

50 Fig. 6 is a transverse sectional view

through the secondary combustion chamber on line 6—6 of Fig. 7;

Fig. 7 is a longitudinal sectional view upon line 7—7 of Fig. 5; and

Fig. 8 is a perspective view of the fuel and 55 air supply pipes with the associated parts indicated in dotted line.

Like numerals designate corresponding parts throughout the several figures of the drawings.

In the form of the invention illustrated in Figs. 1 to 4, 5 designates the primary combustion chamber which is of circular formation and lies with its axis substantially horizontal. The front of the primary combustion chamber 5 is closed by a plate 6 which may be of fire-brick or other heat resisting material. A door 6^a disposed outwardly of the plate 6 is hinged, as indicated at 6^b. Latches 28 are pivoted to the door 6^a at 28^a and cooperate with the keepers 28^b. An operating handle 8 is common to a pair of links 29 to the ends of which links these latches 28 are pivotally connected. Thus upon shifting of the handle either to the 75 right or to the left, the latches will be actuated to lock the door in closed position or to release the same as the case may be. The circumferential wall of the primary combustion chamber 5 is formed of fire-brick 80 or other highly heat resistant material and, if desired, this fire-brick may be enclosed within a metallic shell 5^a (see Fig. 4). At its rear end the combustion chamber 5 opens into the coniform combustion chamber 9, 85 hereinafter referred to as the secondary combustion chamber. The walls of this chamber are also of fire-brick or other highly heat resistant material and the same is true of a cap or closure 32 seated upon the top of the material 31 within which the chamber 9 is formed. A discharge pipe 10 for the products of combustion passes laterally from the upper end of the coniform secondary combustion chamber 9 and is preferably disposed tangentially with respect thereto and is formed in the fire-brick material 31.

In the form of the invention shown in Figs. 5, 6, 7 and 8 the fuel consisting of a mixture of powdered coal and air is fed 100

through a pipe 2 tangentially into the primary combustion chamber 5^x. In addition to this air may be supplied through a pipe 1 to the housing A' of the furnace with 5 in which the several parts are enclosed. This air rises and after becoming heated enters a pipe 13 passing downwardly through said pipe into a pipe 14 and being thereby discharged through the branch 10 pipes 16 and 17 into the lower part of the secondary combustion chamber 9^x and into the primary combustion chamber 5^x respectively. The discharge of this air into the primary combustion chamber is at a 15 point further on in the circumference of this chamber than the point at which the pipe 2^x enters and the entry of the branch pipe 16 into the lower portion of the secondary combustion chamber 9^x is at such 20 an angle as to keep up the whirling action which has been imparted to the air and powdered coal dust and the products of combustion in the primary combustion chamber. By an inspection of the drawings 25 it will be seen that the lower rear side of the secondary combustion chamber opens into the rear end of the primary combustion chamber. Thus the products of combustion with a whirling motion imparted 30 thereto pass from the primary combustion chamber into the secondary combustion chamber while the rear wall of the secondary combustion chamber acts to reflect heat from its highly heated surfaces back 35 into the primary combustion chamber to heat up the incoming fuel to the point of ignition.

By virtue of this construction I am enabled to get substantially perfect combustion 40 and if it were not for this construction, there would be a likelihood of the coarse coal being carried into the secondary combustion chamber before becoming completely ignited for the reason that there 45 would not be sufficient heat in the primary combustion chamber to heat the incoming fuel above the kindling point.

The invention contemplates the provision 50 of a steam pipe 18 entering the lower portion of the pipe 17 and acting as a blower both to force the air with great velocity into the primary combustion chamber and to draw the heated air more rapidly through the pipe 13. Any slag which 55 drops into the pipe 16 from the secondary combustion chamber 9^x will be collected in the pipe 19 which constitutes an extension of the pipe 14 (see Fig. 8). In like manner an extension 15 of pipe 17 collects any 60 slag that may drop into the pipe 17 from the primary combustion chamber, this extension 15 directing such slag into the pit 20^x (see Fig. 8).

Figs. 2 and 4 differ from Figs. 5 and 7 65 in that in Figs. 2 and 4 the supply pipe

2 for the fuel is provided with two branches which enter the primary combustion chamber at different points in its circumference, these branches being designated 2^a and 2^b;—otherwise the structures are, practically, the 70 same, except that in Figs. 2 and 4 clean-out openings 15^a and 19^a are provided for the primary and secondary combustion chambers, these clean-out openings being provided with doors 15^b and 19^b, respectively, which doors close by gravity. The material 31^x and 32^x of Fig. 7 corresponds to the parts 31 and 32 in Fig. 4 and pipe 10^x of Figs. 5 and 7 corresponds in function to flue 10 of Fig. 4. 80

Pit 20 is preferably provided with a door 30 in Fig. 4 and pit 20^x is provided with a door 30^x in Fig. 7 through which ashes or clinkers may be removed from said pit.

It is to be understood that the invention is not limited to the precise construction set forth but that it includes within its purview whatever changes fairly come within either the terms or the spirit of the appended claims. 85

Having described my invention what I claim is:

1. A furnace of the character described comprising a primary combustion chamber of cylindric formation disposed with its axis substantially horizontal and a secondary combustion chamber of substantially inverted coniform shape, the side of the lower portion of which is in communication with an end of the primary combustion chamber, means for feeding fine fuel in suspension tangentially into the primary combustion chamber, means for supplying air under pressure tangentially to the primary combustion chamber and means for supplying air under pressure to the lower part of the secondary combustion chamber at an angle to the axis thereof. 95

2. A structure as recited in claim 1 in combination with an enclosing casing for said chambers and means for taking the air supplied to said primary and secondary combustion chambers from a point within said casing. 110

3. A structure as recited in claim 1 in combination with a casing enclosing said combustion chambers, a pipe in communication with said air supply pipe and taking its supply from a point within said casing and a steam jet pipe leading into said air supply pipe for inducing forced draft therein. 115

4. A furnace of the character described comprising a primary combustion chamber of substantially cylindric form with its axis horizontally disposed and a secondary combustion chamber of substantially inverted coniform shape the side of the lower end of which is in communication with an end of the primary combustion chamber, a cas- 125

ing within which said chambers are enclosed, a pipe located within said casing and a pair of branch pipes communicating with said pipe, one of which branch pipes discharges tangentially into the primary combustion chamber and the other of which discharges at an angle into the lower end of the secondary combustion chamber.

5. A structure as recited in claim 4 in combination with a steam jet communicating with said branch pipe for inducing a forced draft therein.

JOHN TAYLOR.
